UNITED STATES PATENT OFFICE.

JAMES C. GOURLEY, OF HARTFORD, CONNECTICUT, ASSIGNOR TO THE SMYTH MANUFACTURING COMPANY, OF HARTFORD, CONNECTICUT, A CORPORATION OF CONNECTICUT.

MACHINE FOR SHAPING THE BACKS OF BOOK-COVERS.

1,230,292.

Specification of Letters Patent. Patented June 19, 1917.

Application filed February 19, 1916. Serial No. 79,320.

To all whom it may concern:

Be it known that I, JAMES C. GOURLEY, a citizen of the United States, residing at Hartford, in the county of Hartford and 5 State of Connecticut, have invented a new and useful Improvement in Machines for Shaping the Backs of Book-Covers, of which the following is a specification.

A book cover or case has two, more or less 10 stiff, sides flexibly joined to a back. The case of the most common form of book has the two sides stiffened by paper or pulp boards and the intermediate back lined with thin paper or cloth, these being applied to 15 the outside covering of cloth, paper, leather or the like material in such manner that the joints between the edges of the sides and the back will be flexible and allow the book to readily open. The machine which forms 20 the subject of this invention is designed to give proper shape to the backs of such cases.

Books vary greatly in length, width and thickness, and may be what is known as "round backed," "flat backed," or "flat 25 back" books, and the cases for these must, of course, vary accordingly. The object of this invention is to provide a simple and efficient machine which can be used to rapidly and cheaply set in the desired shape the 30 backs of book cases of various styles and sizes.

In the machine illustrated the cases are stacked in a magazine, which is adjustable to accommodate various sizes, and one at a time 35 successively removed from the bottom of the magazine and by an adjustable feed carried along between adjustable guides, over a former of the size and style to impart the required shape, and between creasers, adjustable vertically and horizontally, in such 40 manner that the backs are quickly and accurately creased and set in the desired shape. This machine is so designed that it may be used for shaping cases for either round backed books, or flat backed books, or flat back books, by simply changing the former, of any length, width and thickness, within 45 the limits of adjustment of the mechanisms.

Figure 1 of the accompanying illustrations 50 shows a plan of the machine. Fig. 2 shows a front elevation. Fig. 3 shows an elevation of the left hand end. Fig. 4 shows an elevation of the right hand end. Fig. 5 is an enlarged section on line 5—5 on Fig. 1. Fig. 55 6 is a section and Fig. 7 a plan of the chain

feed blocks. Fig. 8 is a section through a former and the creasers of one shape. Fig. 9 is a section of former and creasers of another shape. Fig. 10 shows a former and creasers of another shape. Fig. 11 is a plan 60 of an end of one of the creasers shown in Fig. 10. Fig. 12 shows a side view of the parts shown in Fig. 11.

The magazine for receiving the stack of cases consists of two upright plates 1 that 65 have their lower edges attached to blocks 2 fastened to bars 3 which are movably mounted on the top of the frame bed 4 in such manner that by moving the bars in and out the side plates of the magazine may be adjusted 70 toward or from each other for accommodating cases of different shapes and sizes. These bars extend parallel the length of the bed and are utilized to support the edges of the cases as they are fed through the machine. The bars also carry the wings 5 which guide the cases as they are fed along from the magazine. The wings are desirably jointed, as at 6, and the ends near the magazine are pivoted to the supporting bars, 75 while the other ends are held by adjusting screws 7. This enables the wings to be set so that they will converge for a short distance from the magazine toward the discharge end of the machine and crowd the 80 sides of the cases toward each other as they come from the magazine and thus provide the required amount of slack in the backs to allow them to conform to the shaping former 8, and when the backs are sufficiently 85 slack the wings extend parallel so that the cases will travel along in this condition. The supporting bars bearing the magazine plates and the guiding wings are adjusted 90 toward and from each other by means of screw shafts 9 at each end of the machine, which shafts are connected at the front by bevel gears 10 with a shaft 11 that extends across the front of the machine so that the bars can be moved at both ends coincidentally. 95

The frame at the left hand end near the rear supports a driving shaft 12, with a pulley 13 and a clutch 14 on the rear end of the shaft. A shipper rod 15 is arranged to extend to the front of the machine and connect with a shaft 16 having a handle 17 by means of which the clutch may be operated for connecting and disconnecting the pulley and the drive shaft. On the driving shaft is a pinion 18 which meshes with a gear 19 on a 100 105 110

countershaft 20 that extends across the left end of the machine. On the countershaft are two sprocket wheels 21. At the right hand end of the machine the frame supports 5 a shaft 22 having two sprocket wheels 23. The shaft at this end is supported by bearings in pillow blocks 24 which are movably mounted on brackets 25 so that the sprockets may be adjusted independently. Sprocket 10 chains 26 extend from end to end of the machine around these sprocket wheels and travel in channels in the top of the bed, passing beneath the open lower end of the magazine. On these sprocket chains at suitable intervals are blocks 27. These blocks 15 are removably fastened to links of the chain and attached to each block is a spring plate 28 that may have its front end raised the desired amount by a plunger 29 beneath it and an adjusting screw 30 which is adapted 20 to turn against the plunger from one side of the block. By turning these adjusting screws the plungers may be forced up so as to lift the front edges of the plates above the 25 surfaces of the blocks sufficiently to engage the edges of the sides of the lower case in the stack in the magazine. The feed blocks on the chains are guided by the walls 31 of the channels in which they run, and on one 30 side the blocks have a tongue 32 that fits an undercut opening in the outer wall of the channel, for the purpose of holding the blocks down as they pass through the channels from one end of the machine to the 35 other. The position of the pusher blocks can be altered on the chains for various sizes of cases, and the pusher plates on the blocks may be adjusted for cases of different thickness.

40 On top of the bed between the channels which form the guides for the chains and feed blocks is a bar 33 to the upper face of which is fastened the shaping former 8. This former tapers outwardly for a short distance from the magazine, and near its other end it is full size. The cross sectional contour of the former is such that at the end where it is full size it is just the size and shape of the inside of the back which it is to 45 form. These forming bars are of different sizes and shapes and are changed for forming backs of different sizes and shapes. Beneath the forming bar is a pipe 35 provided with jet openings. This pipe is adapted to 50 be connected with a gas supply, which when turned on and ignited, will keep the former sufficiently warm for it to accomplish its function of shaping the backs of the cases. As the cases are fed along by the 55 blocks on the feed chains with their sides resting on the supporting bars and between the guide wings the backs travel above the forming bar. As stated, the bar is tapered so that it is somewhat smaller at the 60 magazine end than at the other end which

65

has the correct contour to give the inside of the cover the required shape. This enables the covers to readily pass onto the former as they are carried along by the feed blocks. The heat of the gas flame is utilized 70 to soften the glue or other adherent which has been employed to secure the back linings to the outer facing or covering of the cases.

As the cases are fed along the supports by the feed chain blocks between the guides 75 and over the former, the edges of the backs pass between two creaser bars 36. These creaser bars may be set so that their inner faces are somewhat inclined toward each other and they are shaped to press the cases 80 along the edges of the sides and make the hinge creases between the backs and the sides, and at the same time hold the backs tightly down on the heated forming bar and cause them to assume the correct shape. 85 These creasing bars are attached to sleeves 37 which are arranged to slide along bars 38 that extend from front to back and are supported at each end by a frame 39. The sleeves are adjusted toward or from each 90 other by screw rods 40 which are connected by bevel gears 41 with a rod 42 at the front. The creaser supporting frame is movably retained by brackets 43 at the front and back and is adjusted vertically by means of screws 95 44 which are threaded into the frame and are by beveled gears 57 geared to side rods 45 that are connected by bevel gears 46 with a rod 47 at the front, so that by turning the rods and screws the frame with the creasers 100 may be adjusted up and down. By this mechanism the creasers may be adjusted horizontally toward or from each other, also vertically toward or from the bed.

The frame which moves up and down and carries the creasers also carries holding down bars 48. These holding down bars are supported at each end by screws 50 turning through the sides of the frame so that each end of the bars may be adjusted independently of the frame according to the thickness of the sides of the cases and the manner it is desired to have the bars act on the cases, that is, the magazine ends of the holding bars may be a little higher than the other ends if it is desired.

In Fig. 5 the former is shown as shaped for forming cases "round backed" books, and in Fig. 8 the former is designed to shape cases for "flat backed" books. In these instances the creasers are shown as adapted to tuck the edges of the backs inward. Fig. 9 shows the former as adapted to shape a case for a "flat back" book. Fig. 10 shows a rounded former 51 with creaser bars 52 that 125 crease the backs close to the edges of the sides. In this case the creasers are mounted upon bars 53 that are fastened to the sleeves 37 which are supported by the vertically adjustable frame 39. By turning the screw 130

54 and moving the creaser bar longitudinally it can be adjusted vertically. This action is desirably attained by making a diagonal groove 55 in the bar and providing the back 5 of the creaser with a dove-tail tongue 56. The bars 53, by moving the frame up and down, can be adjusted according to the thickness of the sides so as to hold the sides down, and the creasers can be adjusted independently of the bars so as to force down 10 the backs and form the creases close to the edges of the sides.

With this machine cases for books of any length, width and thickness, within the 15 limits of the machine, may be stacked in the magazine which is adjustable so that it will properly hold the cases of different sizes. The feed blocks are adjusted according to the length and thickness of the cases, and 20 they engage the edge of the lowest case in the stack and push it out of the magazine, carrying it along on the supporting bars while the guide wings crowd the sides together so as to give the backs the necessary 25 slack. The backs pass onto the tapering former which gradually increases in size so as to give the backs the desired shape, and at the same time the creasers between which the backs pass put in the creases and hold 30 the backs tightly down to the former which is warm so the backs will be set in shape. The supporting bars and wings are adjustable sidewise with the magazine walls, and the creasers holding down bars are moved up 35 and down together so they can be located in suitable position, and the holding down bars and creasers are independently adjustable vertically so that they will properly hold down and crease the cases, while the 40 creasers are independently adjustable sidewise.

The invention claimed is;

1. A machine for shaping the backs of book covers or cases having means for engaging the sides of the opened cases and 45 feeding the cases edgewise through the machine, means engaging the insides of the backs of the cases as they are fed for imparting the desired form to the backs, and means 50 engaging the outsides of the backs adjacent to the junction of the backs and sides for holding the backs down closely to the forming means as the cases are carried along.

2. A machine for shaping the backs of 55 book covers or cases having means for engaging the sides of the opened cases and feeding the cases edgewise through the machine, a fixed forming bar for engaging the insides of the backs of the cases as they are fed, and creasers for stretching the backs of 60 the cases over the forming bar as the cases are carried along.

3. A machine for shaping the backs of book covers or cases having a magazine for 65 receiving a stack of opened cases, means for

feeding the cases successively edgewise out of the magazine, a fixed forming bar over which the cases are fed for shaping the backs of the cases, and creasers for stretching the backs of the cases over the forming 70 bar as the cases are carried along.

4. A machine for shaping the backs of book covers or cases having means for engaging the sides of the opened cases and feeding the cases edgewise through the machine, a former over which the cases are fed for shaping the backs of the cases, means for heating the former, and creasers for stretching the backs of the cases over the former as the cases are carried along. 75

5. A machine for shaping the backs of book covers or cases having means for engaging the sides of the opened cases and feeding the cases edgewise through the machine, a former over which the backs of the 80 cases are fed, and creasers in contact with which the backs pass and under which the sides pass as the cases are fed.

6. A machine for shaping the backs of book covers or cases having means for engaging the sides of the opened cases and feeding the cases edgewise through the machine, a former over which the cases are fed for shaping the backs of the cases, wings 85 engaging the edges of the sides for guiding 90 the cases over the former, and creasers for holding the backs of the cases closely to the former as they are carried along.

7. A machine for shaping the backs of book covers or cases having a magazine for 100 receiving a stack of opened cases, means for engaging the sides of the opened cases and feeding the cases successively edgewise out of the magazine, a former over which the cases are fed for shaping the backs of the 105 cases, wings engaging the edges of the sides for guiding the cases over the former, and creasers for stretching the backs of the cases over the former as they are carried along.

8. A machine for shaping the backs of book covers or cases having means for engaging the sides of the opened cases and feeding the cases edgewise through the machine, a former over which the cases are fed for shaping the backs of the cases, creasers 115 for stretching the backs of the cases over the former as they are carried along, and means for adjusting the creasers horizontally and vertically.

9. A machine for shaping the backs of book covers or cases having a magazine for 120 receiving a stack of opened cases, wings engaging the edges of the sides of the cases for guiding the cases as they are fed, means for coincidently adjusting the magazine walls 125 and wings for cases of different sizes, means for engaging the sides of the cases and feeding the cases edgewise successively out of the magazine, a former over which the cases are fed for shaping the backs of the cases, 130

- creasers for holding the backs of the cases to the former as they are carried along, and means for adjusting the creasers horizontally and vertically.
- 5 10. A machine for shaping the backs of book covers or cases having chains and blocks attached to the chains for engaging the sides of the cases and feeding the cases through the machine, fixed means over 10 which the cases are fed for engaging the insides of the backs and imparting the desired form, and means engaging the outsides of the backs adjacent to the junction of the backs and sides for holding the back 15 to said forming means as the cases are carried along.
11. A machine for shaping the backs of book covers or cases having a magazine for receiving a stack of opened cases, chains 20 with feed blocks passing beneath said magazine, means over which the cases are fed for engaging the insides of the backs and imparting the desired form, and means engaging the outsides of the backs adjacent to the 25 junction of the backs and sides for holding the backs to said forming means as the cases are carried along.
12. A machine for shaping the backs of book covers or cases having a magazine for receiving a stack of opened cases, means for 30 adjusting the sides of the magazine toward and from each other, means for engaging the sides of the cases and feeding the cases edgewise successively out of the magazine, a former over which the cases are fed for shaping the backs of the cases, and creasers for stretching the backs of the cases over the former as they are carried along.
13. A machine for shaping the backs of book covers or cases having a magazine for receiving a stack of opened cases, means for 40 engaging the sides of the opened cases and feeding the cases edgewise successively from the magazine, a former that increases in size 45 from the magazine outward over which the cases are fed for engaging the insides of the backs and imparting the desired shape, and creasers engaging the outsides of the backs adjacent to the junction of the backs 50 and sides and holding the backs to the former as the cases are carried along.
14. A machine for shaping the backs of book covers or cases having means for engaging the sides of the opened cases and 55 feeding the cases edgewise through the machine, a fixed former over which the cases are fed for imparting the desired shape to the backs of the cases, a gas burner beneath the former for heating the former, and 60 creasers engaging the backs adjacent to the junction of the backs and sides for holding the backs of the cases to the former as they are carried along.
15. A machine for shaping the backs of 65 book covers or cases having a magazine for receiving a stack of opened cases, means for engaging the sides of the opened cases and feeding the cases edgewise successively out of the magazine, a fixed former over which the cases are fed for imparting the desired shape to the backs of the cases, converging wings engaging the edges of the sides of the cases for guiding the cases over the former, means for adjusting the convergence of said wings, and creasers engaging the backs adjacent to the junction of the backs and sides for holding the backs of the cases to the former as they are carried along.
16. A machine for shaping the backs of book covers or cases having a magazine for receiving a stack of opened cases, means for 70 engaging the sides of the opened cases and feeding the cases edgewise successively out of the magazine, a former over which the cases are fed for imparting the desired shape 75 to the backs of the cases, bars for supporting the sides of the cases, wings mounted on said bars and leading from the magazine for engaging the edges of the sides and guiding the cases as they are fed, and creasers engaging the backs of the cases adjacent to the junction of the backs and sides for holding the backs of the cases to the former as they are carried along.
17. A machine for shaping the backs of book covers or cases having means for engaging the sides of the cases and feeding the cases edgewise through the machine, a former over which the cases are fed for shaping the backs, creasers in contact with which the backs pass and under which the sides pass as the cases are fed, and means for adjusting said creasers toward and from each other.
18. A machine for shaping the backs of book covers or cases having chains, blocks 90 adjustably mounted on said chains and push plates adjustably mounted on the blocks for feeding the cases edgewise through the machine, fixed means over which the cases are fed for engaging the insides of the backs and imparting the desired form thereto, and means engaging the outsides of the backs adjacent to the junction of the backs and sides for holding the back closely to the 95 forming means as the cases are carried along.
19. A machine for shaping the backs of book covers or cases having means for engaging the sides of the opened cases and 100 feeding the cases edgewise through the machine, means for holding down the sides of the cases, a former over which the cases are fed for shaping the backs of the cases, jointed wings engaging the edges of the sides for 105 guiding the cases over the former, and creasers engaging the backs adjacent to the junction of the backs and sides for holding the backs of the cases closely to the former 110 as they are carried along.
- 130

20. A machine for shaping the backs of book covers or cases having a magazine for receiving a stack of opened cases, means for engaging the sides of the cases and feeding the cases successively edgewise from the bottom of the magazine through the machine, holders for engaging and retaining the sides of the cases flat, guides for engaging the edges of the sides and forming a path for the cases, a former over which the cases are fed for shaping the backs of the cases, creasers for engaging the backs of the cases adjacent to the junction of the backs and sides and holding the backs of the cases to the former as they are carried along, and means for adjusting said holders vertically and creasers horizontally and vertically.
21. A machine for shaping the backs of book covers or cases having means for engaging the sides of the opened cases and feeding the cases edgewise through the machine, a former over which the cases are fed for engaging the insides of the backs and imparting the desired shape, creasers under which the cases are fed for engaging the outsides of the backs close to the inner edges of the sides for holding the backs to the former and creasing the backs as the cases are carried along, creaser supporting bars adjustable toward and from each other, and means for adjusting the creasers up and down on said bars.
